UNITED STATES PATENT OFFICE.

JOSEPH WALLACE WOOD, OF MAYSVILLE, GEORGIA.

DESIGN FOR A GRAFT-CUTTING BLADE.

SPECIFICATION forming part of Design No. 30,675, dated May 2, 1899.

Application filed March 29, 1899. Serial No. 711,021. Term of patent 14 years.

To all whom it may concern:

Be it known that I, JOSEPH WALLACE WOOD, a citizen of the United States, residing at Maysville, in the county of Jackson and State of Georgia, have invented and produced a new and original Design for a Graft-Cutting Blade; and I do hereby declare the following to be a full, clear, and exact description of the invention, such as will enable others skilled in the art to which it appertains to make and use the same.

My invention relates to a design for a graft-cutting blade; and the design consists of a blade having the following essential features, viz: a flat backing and two sharp straight edges in different planes parallel to the general plane of the blade, connected at their adjacent ends midway the length of the blade by a short sharp edge lying in a plane transverse to the general plane of the blade, as shown in the accompanying drawings.

In the accompanying drawings, which illustrate a graft-cutting blade embodying my design, Figure 1 represents a perspective view showing one side of the blade. Fig. 2 represents a perspective view showing the other

side of the blade. Fig. 3 is an elevation of one side of the blade. Fig. 4 is an elevation of the other side of the blade, and Fig. 5 is a section taken on the line 55 in Fig. 3 and looking in the direction of the arrow in said figure.

1 designates the backing or body of the blade, which is flat.

2 2 designate the long cutting edges lying parallel to the plane of the blade and each being substantially the length of half the whole length of the blade, and 3 designates the short transverse cutting edge connecting the adjacent ends of the edges 2 2.

The inner face of each of the edges 2 2 is beveled, as shown at 4 4, while the outer faces 5 5 thereof are straight and flat.

What I claim is—

The design for a graft-cutting blade, substantially as herein described and shown. 45

In testimony whereof I affix my signature in presence of two witnesses.

JOSEPH WALLACE WOOD.
